L. J. ANSHEN

ORNAMENTAL CHAIN

Filed Oct. 25, 1924

Louis J. Amherst
By Horatio E. Bellows
Attorney.

UNITED STATES PATENT OFFICE.

LOUIS J. ANSHEN, OF PROVIDENCE, RHODE ISLAND.

ORNAMENTAL CHAIN.

Application filed October 25, 1924. Serial No. 745,820.

To all whom it may concern:

Be it known that I, LOUIS J. ANSHEN, a citizen of the United States, residing at Providence, in the county of Providence and State of Rhode Island, have invented certain new and useful Improvements in Ornamental Chains, of which the following is a specification.

My invention relates to chains adapted for use in articles for personal adornment such as bracelets, girdles, and the like, and for other ornamental purposes.

The essential objects of my invention are capacity for expansion and flexibility; freedom from lateral play of the links even when expanded; security and strength of parts; freedom from derangement of the springs; compactness; and simplicity of construction.

20 My invention consists in the means for producing the results specified substantially as hereinafter claimed.

In the accompanying drawings illustrating the principle of this invention

25 Figure 1 is a perspective view from the front, of a chain or strap embodying my invention.

Figure 2, a section on line 2—2 of Figure 1,

30 Figure 3, a fragmentary rear elevation of the chain,

Figures 4 and 5, sections taken on lines 4—4 of Figure 3 and 5—5 of Figure 4 respectively,

35 Figure 6, a section corresponding with that of Figure 4, showing the parts expanded, and

Figures 7 and 8, detail inverted perspective views of the outer and inner members of the unit.

40 Similar characters of reference indicate similar parts throughout the views.

As illustrated, my chain or strap consists of a series of units indicated generally by 45 10 each comprising an oblong shell 11, substantially rectangular in cross section consisting of a front wall 12, top and bottom walls 13, vertically directed flanges 14 upon the top and bottom walls substantially 50 parallel with the front wall, and provided at their inner edges, which are spaced from each other, with inwardly directed lips 15 provided at one end with depending projections 16 extending nearly to the front 55 wall. Near each end of the top and bottom

walls are perforations 17 adapted to receive therethrough solid or tubular posts or rivets 18. In this instance notches 20 in the lips 15 correspond in position with the perforations 17 for a like purpose. The flange 14 with its lip 15 combine with the adjacent wall 13 to form a housing 23 separated from its companion housing by a space or guideway 25.

In each shell or tube 11 is slidably 65 mounted a connecting member 27 comprising an oblong plate 28 provided at the extremities of one end with rearwardly directed lugs 29, and having integral with the middle of the other end an arm 30 provided with a rearwardly directed open loop 31 at its point of junction with the plate. This rearwardly extending arm has upon its free end a flat laterally enlarged end portion 32 resting with its entire area 70 against the plate 28 and terminating in projecting portions 33 abutting against the lugs 29, all as shown in Figure 8.

Each plate 28 slides upon the inner face of the front wall 12 of its enclosing shell 80 with its side edges in contact with the top and bottom walls 13 thereof. A portion of that end of the slide with which the arm 30 is integral, which may be called the forward end, projects into the next adjacent shell and loosely surrounds the rearmost post 18 of the latter shell. The elevated portion of the looped arm 31 is a sliding fit in the guideway 25. Within each housing 23 is a helical spring 35 having one end 90 abutting against one of the lugs 29 and its other end engaging the forward post 18 of the enclosing shell. The lugs 29 space one end of the plate 28 from the front and back walls of the shell, while the other end of the plate is spaced from these walls by the lips 15 and projections 16.

In operation, a distension of the parts compresses the springs 35 and separates the shells 11 from each other, disclosing the plates 28 of the connecting members whereby the chain presents from the front a substantially unbroken and ornamental surface. While the members 11 and 27 are usually precious plated metal surface ornamentation may be added to both the shells 11 and the plate 28 if desired.

It will be observed that the longitudinally disposed looped arms 30 movable in the guideways 25 tend to prevent any lat-

eral play between the members 11 and 27; adjacent unit, and compression springs in 20
that lugs 29 and projections 16 have a similar effect upon the members in a forward 25
or rearward direction, that during expansion a smooth movement of the parts is
insured; and that the shells 11 and connecting members 27 may each be formed from
a single blank, thus insuring facile and inexpensive construction.

10 I claim:—

1. In a chain of the type set forth, a series
of connected units, each unit comprising a
wall, housings on the wall parallel with
each other, transversely disposed posts sup-
15 ported in the housings near their ends, a
connecting plate slidably engaging the wall,
lugs upon one end of the plate within the
housings, a loop on the plate between the
housings loosely surrounding a post of an

adjacent unit, and compression springs in 20
the housings engaging the lugs.

2. In a chain of the type set forth, a series
of units, each unit comprising a front wall,
a top wall, a bottom wall, vertical flanges
upon the top and bottom walls, inwardly di-
rected lips upon the flanges, parallel and
25 spaced from each other and provided near
one end with projections, transverse posts
connecting the top and bottom walls near
their ends, a slideable plate engaging the
wall and the projections, lugs on the plate
30 enclosed by the flanges and lips, a loop on
the plate slidably engaging the lips, and
springs engaging the lugs and one of the
posts.

35 In testimony whereof I have affixed my
signature.

LOUIS J. ANSHEN.
